TORQUE TRANSMITTING FLEXIBLE COUPLING FOR ROTATABLE SHAFTS

Thomas L. Fawick, Shaker Heights, Ohio, assignor to
Eaton Yale & Towne Inc., Cleveland, Ohio, a corpora-
tion of Ohio

Filed Oct. 5, 1967, Ser. No. 8,874

Term of patent 14 years

Int. Cl. D15—99

U.S. Cl. D55—1

Fig. 1

Fig. 4

Fig. 5

Fig. 6

Fig. 7

Fig. 8

FIGURE 1 is an end elevational view of a single flexible coupling in accordance with a first embodiment of my new design, taken from the left end of FIG. 2;

FIGURE 2 is a side elevational view of the FIG. 1 coupling;

FIGURE 3 is an end elevational view of the coupling of FIGS. 1 and 2, taken from the right end of FIG. 2;

FIGURE 4 is a perspective view of the coupling of FIGS. 1-3, taken from the left end of FIG. 2;

FIGURE 5 is a perspective view of the coupling of FIGS. 1-3, taken from the right end of FIG. 2;

FIGURE 6 is a side elevational view of a dual flexible coupling in accordance with a second embodiment of my design, which consists of two of the single couplings as shown in FIGS. 1-5 connected end-to-end;

FIGURE 7 is a side elevational view of a dual flexible coupling in accordance with a third embodiment of my design, each half of which is essentially the same in end elevation as the embodiment of FIGS. 1-5 except for the absence of bolts; and

FIGURE 8 is a side elevational view of a single flexible coupling in accordance with a fourth embodiment of my design which differs from the embodiment of FIGS. 1-5 only in the position of the plate on the left end of the coupling.

I claim:

The ornamental design for a torque transmitting flexible coupling for rotatable shafts, substantially as shown and described.
